UNITED STATES PATENT OFFICE.

ROBERT B. HOUGH, OF ERIE, PENNSYLVANIA.

FOOT-SCRAPER.

SPECIFICATION forming part of Letters Patent No. 252,669, dated January 24, 1882.

Application filed May 21, 1881. (No model.)

To all whom it may concern:

Be it known that I, ROBERT B. HOUGH, a resident of Erie, Erie county, Pennsylvania, and a citizen of the United States, have invented new and useful Improvements in Foot Scrapers and Cleaners; and I do hereby declare that the following is a full, clear, and exact description thereof, reference being had to the accompanying drawings and the letters or figures of reference marked thereon.

My invention relates to foot-scrapers with cleaning-brushes attached; and it consists in certain improvements in the construction thereof, which will be hereinafter fully described and pointed out.

In the accompanying drawings my device is shown as follows:

Figure 1 is a perspective view of my foot scraper and cleaner placed in a pan provided purposely therefor. Fig. 2 is a longitudinal section of the pan through the legs thereof. Fig. 3 is a side view of my device, and shows the same attached to a door-step without a pan. Fig. 4 is a top view of the same, with parts of the brushes broken away to show the construction below. The pan is not shown in this figure.

The letters of reference indicate parts as follows:

A is the pan, and *a* the rubber tips or feet set in the socket shaped legs. B B' B'' is the frame-work, of which B serves as a scraper, and has a foot guide or deflector, *b*, extending therefrom in the direction from which the foot enters the cleaning apparatus.

C C are the side or wing brushes, which are attached to pivoted spring-arms F, which are pivoted on the standards E, which spring up or rise from the part of the frame marked B'.

G are the springs which operate the wing-brushes, and have their coils arranged within the standards E, which coils may be of greater or less length, as is shown in Figs. 1 and 3.

D is the brush which operates upon the bot-

tom of the foot after it has been upon the 45 scraper. This brush is attached firmly to the part of the frame marked B'' by screws, as shown in Fig. 3. The foot enters the device heel first from the left of Figs. 1, 3, and 4. It is brushed on the side by brushes C C and is 50 scraped on the bottom by scraper B and brushed by brush D.

I am aware that Patents No. 23,419 and No. 76,866 to W. L. Williams, dated respectively March 29, 1859, and April 14, 1868, show 55 both side and bottom brushes and the scraper and pan, and also show the side brushes constructed with springs. I therefore do not claim broadly any of these devices, nor do I claim a device having them all in combination. 60

My device is so constructed that it can be used within a pan or attached to the floor or door-step. The deflector *b* greatly assists the work of cleaning, as it raises the heel of the boot onto the scraper. The rubber tips on the 65 pan prevent it marring the floor or making a noise if moved about.

What I claim as my invention is—

1. In a boot cleaning and scraping apparatus, the combination, with the bottom and 70 side brushes, of the frame-work B B' B'', standards E E, with springs G G, and pivoted frames F F, the part B of said frame serving as a scraper, and being provided with a deflector, *b*, and said frame B B' B'' being adapted, substantially as shown, to be attached to a pan or to 75 a floor or door-step.

2. In a foot-cleaning apparatus, a sole-scraper having a deflector, *b*, substantially as and for the purposes set forth. 80

In testimony that I claim the foregoing I have hereunto set my hand this 2d day of May, 1881.

ROBT. B. HOUGH.

Witnesses:

JNO. K. HALLOCK,
JOHN FERRIER.
